MECHANICAL PENCIL

Lucifer J. Most, Hudson County, N. J.

Application March 18, 1939, Serial No. 262,589

10 Claims. (Cl. 120—18)

My invention relates to mechanical pencils of the type disclosed in my pending application, Serial Number 208,739, filed May 19th, 1938.

The object of the invention is to provide a simple mechanism, formed of few moving parts, for propelling, repelling, expelling and automatically presenting a new lead to writing position.

Another object of the invention is to provide a mechanical pencil in which the lead itself is part of the feed mechanism.

In the appended drawing forming part of this application,

Figure 1 is an elevation, partially in section, on line 1—1, Figure 2.

Figure 2 is an enlarged cross-section on line 2—2, Figure 1.

Figure 3 is also an enlarged section on line 3—3, Figure 1.

Figure 4 is an enlarged fragmentary cross-section on line 4—4, Figure 3, showing only the parts of the lead feeding means.

Figure 5 is a cross-section on line 5—5, Figure 4.

Figure 6 is a similar section on line 6—6, Figure 4, and

Figure 7 is a modified form of a lead guide in the lead feeding means.

Referring to the drawing, 10 is an outer shell or barrel of the pencil which is open at the upper end and tapered to a hollow tip 11 at the other end. The end of the tip is truncated to form a lead outlet opening 12. In line with the opening 12 and coaxially with the barrel is a lead guide 13 of angular cross-section, in this particular case, triangular. It is properly supported and secured within the tip by a washer plug 14. The lower end of the lead guide 13 is preferably flush with the end 12 of the aperture in the tip.

The upper end of said guide has as many prongs 15 as there are sides to the guide. The width of the prongs 15 is such that they can freely pass through the die or nut 16 without touching its threads when positioned coaxially with said guide 13. In forming the prongs from the body of the lead guide, shoulders 17 are formed, which constitutes a bearing for the lower end 18 of the die 16. To prevent the die 16 from moving longitudinally of said guide, the protruding ends 19 of the prongs 15 are bent over the upper end 20 of the die 16 to maintain said die on the shoulders 17.

The die 16 is housed and secured in a tubular extension 21, forming part of the hopper 22 of a magazine 23, which is revolvably mounted in the

barrel 10. Housed and secured within the tubular member 21 is a sleeve 24, which is positioned above the die 16, clearing the bent ends 19 of the prongs 15. The diameter of the sleeve is just sufficient to clear the edges of the lead moving therethrough. In other words, when the magazine is revolved by the end 25 thereof protruding from the upper end of the barrel, it will only revolve the die 16 connected thereto and the sleeve 24 therein, but will not entrain a lead that 10 is positioned in the sleeve 24. The lower end of the magazine is preferably centered by a ring 26 to maintain die in proper alignment with the lead guide 13.

The longitudinal displacement of the magazine 15 in the barrel is preferably prevented by a ring 27, located between two protruding beads 28, formed in the lateral surface of the magazine near the protruding portion 25 thereof. This ring 27 has a frictional engagement with the inside of 20 the barrel so that it requires an effort to move it longitudinally, but the magazine is free to revolve relatively to the ring. This is an additional precaution as the magazine is prevented from longitudinal movement by the engagement of 25 the die 16 between the shoulders 17 on the bent ends 19 of the prongs 15.

A triangular lead 29, entering from the magazine 23 into sleeve 24, will be guided thereby toward the die 16 and the prongs 15, located in 30 the die 16, will force the triangular lead to present itself so that the lateral sides of the lead 29 will contact with the sides of the prongs 15, the thread edges of said lead engaging the threads of the die. Since the lead engaged by the prongs 35 can not turn when the die 16 is turned through the magazine, the lead will be forced to move longitudinally, since the die is prevented from longitudinal movement by its engagement with the lead guide 13, of which the prongs 15 form 40 an integral part. As long as there is a lead portion located within the die 16, it will be forced to proceed in the direction according to the direction of rotation of said die by the turning of the magazine.

To prevent a section of the lead passing the die from dropping out, the lower end, either of the guide or the tip 12, is made to have a frictional engagement with the lead passing therethrough, so that the section below the die in 50 the lead guide is forced through said guide by the succeeding lead progressing through the die.

In the modified form of the feeding mechanism, shown in Figure 7, the sleeve 24' is part of the lead guide 13'. The sleeve is secured to the pro- 55

truding ends 19' of the prongs 16' and, therefore, the tubular portion 21' is stationary relative to the magazine.

5 The die 16' is split so that the same can be positioned between the shoulders 17', formed between the prongs by lead guide 13' and sleeve 24', and the split ring is secured to the tubular extension 24' from the hopper 22'.

10 In this particular structure, a triangular lead entering the sleeve 24' will be guided more easily into the die in the proper engagement with the prongs, as, under no circumstances, may it be entrained by the rotation of the sleeves, for in this particular case, the sleeve is stationary, relative to the rotating magazine.

15 I claim:

1. In a mechanical pencil, a barrel having a tip forming a lead outlet, a lead guide within the barrel at the outlet, said guide being adapted to prevent a lead from turning therein while permitting a lead to move longitudinally of said guide, a threaded die for engaging a lead directly, and associated with the guide to turn relatively thereto but prevented from moving longitudinally of said guide, and means for turning the die operable at the end of the barrel remote from the tip.

20 2. In a mechanical pencil, a barrel having a tip forming a lead outlet, a lead guide within the barrel at the outlet, said guide being adapted to prevent a lead from turning therein while permitting a lead to move longitudinally of said guide, a threaded die for engaging the lead directly mounted on said guide to turn relatively thereto and to prevent it from moving longitudinally of said guide, and means for turning the die operable at the end of the barrel remote from the tip.

25 3. In a mechanical pencil, a barrel having a tip presenting a lead outlet, the lead magazine 30 revolvable in said barrel, a lead guide at the outlet secured to the barrel, said guide being adapted to prevent a lead from turning therein while permitting a lead to move longitudinally of said guide, a threaded die for engaging a lead directly 40 mounted to revolve on said guide, but prevented from moving longitudinally thereof, said die being coupled to the magazine to revolve therewith.

45 4. In a mechanical pencil, a barrel having a tip presenting a lead outlet, a lead magazine revolvable in said barrel, a lead guide at the outlet secured to the barrel, said guide being adapted to prevent a lead from turning therein while permitting said lead to move longitudinally of said guide, a threaded die for engaging a lead directly, 50 prongs extending from the guide through the die so that the die is free to revolve about the prongs, but prevented from moving longitudinally of said prongs, said die being coupled to the magazine to revolve therewith.

55 5. In a mechanical pencil, a barrel having a tip presenting a lead outlet, a lead magazine revolvable in said barrel, a lead guide at the outlet secured to the barrel, said guide having prongs adapted

to engage a lead to prevent it from turning while permitting it to move longitudinally of said prongs, a threaded die revolvably mounted about said prongs, said prongs having means to prevent said die from moving longitudinally thereof, means coupling the magazine to the die to revolve therewith, and means in said coupling means for guiding a lead to the prongs.

6. In a mechanical pencil, a barrel having a tip presenting a lead outlet, a lead magazine revolvable in said barrel, a lead guide at the outlet secured to the barrel, said guide having prongs adapted to engage a lead to prevent it from turning while permitting it to move longitudinally of said prongs, a threaded die revolvably mounted 15 about said prongs, said prongs having means to prevent said die from moving longitudinally thereof, means coupling the magazine to the die to revolve therewith, and means for said coupling means for guiding a lead to the prongs, so that 20 the lead in said last means is free both to turn and move longitudinally.

7. In a mechanical pencil, a lead magazine, a lead guide from said magazine permitting a lead to move longitudinally therewith and to turn 25 therein, a second lead guide spaced from the first lead guide and in alignment therewith, said second lead guide being adapted to prevent a lead from turning therein, but permitting it to move longitudinally thereof, a threaded die revolvably mounted on said second lead guide, but prevented from moving longitudinally of said second lead guide, and means coupling the die to the magazine.

8. In a mechanical pencil, a barrel having a tip forming a lead outlet, a lead guide within the barrel at the outlet, said guide being adapted to prevent a lead from turning therein while permitting a lead to move longitudinally of said guide, a threaded die for engaging a lead directly 40 revolvably mounted about one end of said guide, and means for turning the die from an end of the barrel.

9. In a mechanical pencil, a barrel having a tip forming a lead outlet, a lead guide within the 45 barrel at the outlet, said guide being adapted to prevent a lead from turning therein while permitting it to move longitudinally of said guide, a threaded die for engaging a lead directly revolvably mounted about a portion of said guide, but 50 prevented from moving longitudinally of said guide, and means for turning the die from an end of the barrel.

10. In a mechanical pencil, a barrel having a tip presenting a lead outlet, a lead guide at the 55 outlet, said guide being adapted to prevent a lead from turning therein while permitting said lead to move longitudinally of said guide, a threaded die for engaging a lead directly, prongs extending from the guide through the die, and means for 60 turning the die relative to the prongs and preventing it from moving longitudinally thereof.

LUCIFER J. MOST.
